INVENTOR.
John P. Doman,

R. W. Smith
ATTORNEY.

UNITED STATES PATENT OFFICE

JOHN P. DOMAN, OF LOS ANGELES, CALIFORNIA

IRONING BOARD

Application filed January 16, 1930. Serial No. 421,127.

This invention is an ironing board having folding legs which may be readily extended or retracted for supporting the board in operative position or forming a compact structure adapted for convenient storage; and it is the object of the invention to provide a folding board of extremely sturdy but simple and inexpensive construction.

It is a further object of the invention to adapt the board for adjustment to different heights, with the desired adjustment made at the time of extending the legs to operative supporting position so as to afford extreme simplicity and convenience in handling.

It is a still further object of the invention to positively lock the board in adjusted position and securely brace it when its legs are unfolded so as to insure a rigid structure.

It is a still further object of the invention to provide a board of usual convergently tapering width toward one end, with the folding legs so arranged as to in no way hinder the user in standing closely adjacent any part of the board but at the same time providing an adequate spaced lateral support for the board.

Further objects of the invention will be readily understood from the following description of the accompanying drawings, in which:

Fig. 1 is a side elevation of the board in operative position, and showing by broken lines the adjustment of the board to a different height.

Fig. 2 is an end view of the board in operative position.

Fig. 3 is a plan view of the board showing its legs folded.

Fig. 4 is a side elevation of the board in folded position.

The ironing board structure comprises a usual ironing board 1 of usual convergently tapering width toward one end and having transversely spaced legs 2 and 3 engaging the underside of the board at its respective ends and crossing medially of their length at a pivotal connection so as to form a rigidly braced support for the board as shown in Figs. 1 and 2. One set of legs, shown as legs 2, are adapted to swing relative to the board

and for this purpose are connected thereto by a pivotal engagement, and the opposite legs 3 have a releasable engagement with the board whereby the legs 2-3 may be fixed in crossed relation as shown in Figs. 1 and 2 55 so as to form a support for the board, or may be folded flat against the underside of the board as shown in Figs. 3 and 4.

The pivotal engagement between legs 2 and the board 1 preferably comprises a transverse block 4 at the wide end of the board and fixed to its underside, with legs 2 pivotally connected to the ends of the block by screws 5; and the medial pivotal connection between legs 2-3 is preferably formed by a 60 transverse pin 6 connecting the legs 2 with legs 3 journaled thereon at the inner sides of legs 2.

The releasable engagement between legs 3 and the board 1 preferably comprises a strip 70 fixed to the underside of the board and extending lengthwise thereof at its convergently tapering end which is remote from pivoted engagement 5, with longitudinally 75 spaced transverse notches 8 in the underside of the strip adapted for selective reception of a transverse pin 9 which connects the proximate ends of legs 3. A cross strip 10 may connect the opposite floor engaging ends 80 of legs 3 which preferably flare to an increased transverse spacing, and the legs 2 preferably similarly flare to an increased transverse spacing toward their ends which are pivoted to block 4 so that when pin 9 is disengaged from notches 8 the legs 2 85 may be swung at their pivotal engagement 5 and at the same time legs 2-3 may be swung at their pivotal connection 6 so that the respective pair of legs lie one within the other in parallel relation and fold flat against the 90 underside of board 1 as shown in Figs. 3 and 4.

The block 4 is preferably of such length transversely of the ironing board that the flaring ends of legs 2 which are pivoted to the ends of the block are transversely spaced so as to lie completely within the transverse width defined by the wide end of the board as shown in Figs. 2 and 3, and the convergence of legs 2 toward their opposite floor 100

engaging ends is preferably such that said floor engaging ends of the legs are transversely spaced so as to lie completely within the transverse width of the convergently tapering end of the board as shown in Fig. 3. The legs 3 being parallel to and pivotally supported at the inner sides of legs 2 are thus also transversely spaced so that their converging ends which are connected by pin 9 lie completely within the transverse width of the convergently tapering end of the board, and in similar manner their flaring ends which engage the floor have the greatest possible transverse spacing while still lying completely within the transverse width of the wide end of the board.

When board 1 is to be supported in operative position the legs 2 are swung at their pivotal engagement 5 and at the same time legs 2-3 are swung at their pivotal connection 6 so that pin 9 may be seated in one of the notches 8, thereby locking the legs in crossed relation by the abutment of pin 9 against the walls of notch 8, and thus forming a support for the ironing board as shown in Figs. 1 and 2.

The cross strip 10 preferably projects laterally beyond flaring legs 3 with its lower side edge adapted to engage the floor when the structure is in operative position as shown in Figs. 1 and 2, thereby providing an appreciable lateral support for preventing transverse tilting of the board; and the cross strip is preferably fixed to the inner sides 35 of legs 3 so as to offer no obstruction to the folding of legs 2-3 one within the other with the cross strip overlying the legs when folded, as shown in Figs. 3 and 4, and the cross strip being of a length to just overlie 40 the legs 2 so that it is completely within the transverse width of the wide end of the board.

By shifting the pin 9 from one to another of the notches 8 the angular relationship of crossed legs 2-3 may be varied so as to adjust 45 just the height of board 1 as shown by broken lines in Fig. 1; with the pivotal engagement between the board and the legs 2 maintaining the board horizontal irrespective of its vertical adjustment.

I have thus provided an ironing board which when in operative position is rigidly supported by crossed legs 2-3 with the transverse strip 10 preventing lateral tilting and the selective engagement of pin 9 in the longitudinally spaced notches 8 varying the height of the board and positively locking it in operative position. The improved construction also provides for readily folding the legs by simply lifting the board so as to disengage pin 9 from notch 8, whereupon the pivoted pairs of legs may be folded one within the other flat against the underside of the board with the cross strip 10 overlying the folded legs, so that the folded structure is

extremely compact and adapted for storage in a relatively small space.

The arrangement of the flaring legs 2-3 as has been described also insures maximum laterally spaced support for the board while maintaining the laterally spacing of the supporting means within the transverse width of a usual board which convergently tapers at one end; and the supporting means will thus in no way hinder the user in standing closely adjacent either end of the board, and the folded legs will take up no greater lateral space than the board itself, but at the same time the floor engaging ends of the legs are sufficiently laterally spaced to insure a firm support for the board.

I claim:

1. In combination, an ironing board convergently tapering in width toward one end, and pairs of transversely spaced legs lying one within the other and pivotally connected medially of their length with the juxtaposed legs of the respective pairs in parallel relation and one pair of legs pivotally engaging one end of the board and the other pair of legs releasably engaging the board at its opposite end, the pairs of legs flaring to increased transverse spacing lengthwise thereof so that the transverse spacing of those portions of the legs beneath the respective ends of the board is no greater than the width of the overlying and respectively wide and convergently tapering ends of the board.

2. In combination, an ironing board convergently tapering in width toward one end, and pairs of transversely spaced legs lying one within the other and pivotally connected medially of their length with the juxtaposed legs of the respective pairs in parallel relation and the pairs of legs flaring to increased transverse spacing lengthwise thereof so that the transverse spacing of those portions of the legs beneath the respective ends of the board is no greater than the width of the overlying and respectively wide and convergently tapering ends of the board, the flaring end of one pair of legs pivotally engaging the wide end of the board, and the other pair of legs releasably engaging the convergently tapering end of the board at the end of said pair of legs which is opposite its flaring end.

3. In combination, an ironing board convergently tapering in width toward one end, and pairs of transversely spaced legs lying one within the other and pivotally connected medially of their length with the juxtaposed legs of the respective pairs in parallel relation and one pair of legs pivotally engaging one end of the board and the other pair of legs releasably engaging the board at its opposite end, the pairs of legs flaring to increased transverse spacing lengthwise thereof so that the transverse width defined by those portions of the legs beneath the respective ends

of the board is substantially equal to but no greater than the width of the overlying and respectively wide and convergently tapering ends of the board.

5 4. In combination, an ironing board convergently tapering in width toward one end, and pairs of transversely spaced legs lying one within the other and pivotally connected medially of their length with the juxtapositioned legs of the respective pairs in parallel relation and one pair of legs pivotally engaging one end of the board and the other pair of legs releasably engaging the board at its opposite end, the outer pair of legs engaging the wide end of the board, and the pairs of legs flaring to increased transverse spacing lengthwise thereof so that the transverse spacing of those portions of the legs beneath the respective ends of the board is no greater

10 than the width of the overlying and respectively wide and convergently tapering ends of the board.

15 5. In combination, an ironing board convergently tapering in width toward one end, 25 pairs of transversely spaced legs lying one within the other and pivotally connected medially of their length with the juxtapositioned legs of the respective pairs in parallel relation and one pair of legs pivotally engaging one end of the board and the other pair of legs releasably engaging the board at its opposite end, the outer pair of legs engaging the wide end of the board, and the pairs of legs flaring to increased transverse spacing 30 lengthwise thereof so that the transverse spacing of those portions of the legs beneath the respective ends of the board is no greater than the width of the overlying and respectively wide and convergently tapering ends

35 of the board, and a floor engaging cross member connecting the underside of that end of the inner pair of legs which is opposite the board engaging end of said legs, with said cross member of a length adapting it to overlie the outer pair of legs without projecting beyond the lateral width of the wide end of the board.

40 In testimony whereof I have affixed my signature.

50 JOHN P. DOMAN.
